To all whom it may concern:

Be it known that I, Howard A. Thede, a citizen of the United States, residing at Wayland, in the county of Allegan and State of Michigan, have invented a new, original, and ornamental Design for a Desk with Drawers, of which the following is a specification, reference being had to the accompanying drawing, forming a part thereof.

I claim:

The ornamental design for a desk with drawers, substantially as shown.

HOWARD A. THEDE.
